THREE-DIMENSIONAL GREETING CARD

Marylka Kellerer, née Bender, Neuilly-sur-Seine, France

Application May 28, 1951, Serial No. 228,558

Claims priority, application France May 31, 1950

3 Claims. (Cl. 41—11)

This invention relates to picture bearing articles and more especially to articles bearing printed pictures such as appear on greeting and menu cards, posters, decorative materials, advertising prints, picture books, informational and educational representations and other reproductions in print on sheet material, and in the first place plain or colored paper, cardboard, sheets of plastic material, textile tissues, metal sheets etc. It is an object of this invention to improve, both in technical and economical respect, the manufacture of articles of the kind aforesaid which display a three-dimensional appearance by virtue of different parts thereof extending and being held in different planes.

Pictures of a similar type as hitherto available consist of separate parts pasted or otherwise connected to each other or to a background sheet, or scored or stamped out and folded to extend in different planes. In the production of these articles the necessity of glueing the parts together was particularly objectionable and the printing had to be done in most cases on both sides of the sheet.

It is an object of this invention to provide a novel form of plastic-appearing picture sheets, consisting, in their simplest embodiment, of a plurality of fragmental coherent portions of a single sheet of paper or other material, all printed with parts of the picture on the same surface of the paper and scored and folded into partial superposition.

It is a further object of this invention to provide a process whereby the new type of plastic-appearing picture bearing articles can be produced on the printing press and/or the stamping die in a single operation which involves a great saving in material and a still greater saving in labor, wages and first cost of the article.

In order to convey a better understanding of my invention and how the same is to be performed, I will now describe it in detail, having reference to the drawings affixed to this specification and forming part thereof, in which several embodiments of my invention are illustrated diagrammatically by way of example.

In the drawings

Figs. 1—4 illustrate one embodiment,

Fig. 1 showing the blank, printed and scored, but not yet folded,

Fig. 2 illustrates on a smaller scale the mode of folding it, while

Fig. 3 shows the finished article, drawn to a slightly larger scale,

Fig. 4 being a diagrammatical representation, in side view, of the different planes in which extend the fragmental portions of which the picture is composed.

Figs. 5—8 illustrate a second embodiment,

Fig. 5 being the blank,

Fig. 6 showing the mode of folding same, while

Fig. 7 is a perspective view of the finished article in open,

Fig. 8 is a plan view in closed position.

Figs. 9 and 10 are diagrams indicating the possibility of making cards or the like offering more than two printed card sections for the composition of a plastic-appearing picture according to this invention.

Fig. 11 illustrates an embodiment utilizing three printed sections, while

Fig. 12 shows a modified form of a card in which two printed sections and two frame sections are combined in the form of a triptych.

Fig. 13 is a perspective view of another embodiment

2

having means for displaying the plastic picture in substantially vertical position.

Fig. 14 is a diagrammatic showing of a card with a covering section which presents retaining edges forming part, not of a frame, but of a mere triangular section.

The feature common to all the embodiments shown on the drawings and which is the most important feature of the articles according to this invention, is the provision of a covering sheet section presenting at least one edge and better still a plurality of edges extending partly or altogether across the underlying sheet section or sections, preferably in the form of a frame of regular or irregular contour, these edges serving as the means for retaining and raising scored parts of one or a plurality of covered (underlying) card sections, all bearing part of picture on the same side of the sheet, raised or pulled by hand above these edges, in a plane or planes different from the plane in which the section is situated, to which they adhere.

20 Referring to the drawings and first to Figs. 1—4, A, B and C are coherent sections of a single sheet of paper, cardboard or other sheet material. The surface of section A as shown in the drawing is the 'rear face' of the section and of the finished card. Sections A and B are rectangles intended to be folded along the line 1 as shown in Fig. 2. Section B is scored along the open oval line 2. Within the oval frame thus formed, the central part of section B is scored along the contours of a vase 3, from which rises a bunch 4 of flowers and leaves. Section C hangs on to the lower part of section A by a connecting piece 5. It is scored along the contours of another bunch 6 of flowers and leaves. The flowers and leaves of bunch 4 are joined together or adhere to the section B only at the points marked 7 and are separated for the greater part from the sheet section and from each other by the cuts 8. By folding section C along the line 9 against the front face 10 (not visible in Fig. 1) of section A, and section B on top of them (Fig. 2) the contours of the vase and the flowers and leaves of both bunches appear in the frame formed by the oval aperture 2, partly overlapping each other.

As shown in Fig. 3, the outermost flowers and leaves of the bunch 6 are raised or pulled by hand through the aperture of the oval frame of section B and the flowers and leaves of bunch 4 which are scored from the material of section B and still adhere to it at some points, are partly pulled through between those of bunch 6, so that now the two bunches are situated in at least two different planes raised above the plane of section B. The dotted lines 11 of reference leading from parts of Fig. 3 to the diagram of Fig. 4 indicate the planes in which the flowers and leaves appear after they have been raised out of the plane, in which this covered section extends. Obviously these raised portions will, at least partly, extend in directions not parallel with the sheet or card section A and thereby increase the appearance of plasticity. By partly overlapping each other, they hinder the onlooker from distinguishing clearly the planes from which they emerge.

On the basis of the representation of section A on the drawing as being viewed from the back, printing of the picture on sections B and C is done on the rear surface of the sheet exclusively, because it is these rear surfaces, that appear as top faces of the finished article.

65 In the card shown in Figs. 5—8 a sheet with the contour of a capital T subdivided into four sheet sections A, B, C, D and printed on three sections B, C and D is folded as shown in Fig. 6, the finished article showing a small part of the picture as being visible through a heart-shaped aperture 14 of section D. Section C is formed with the main frame 15 surrounding the portion 18 cut out and free to be raised out of the plane of section C, this section thus being comparable to section B in Fig. 1. Section B, similarly as section C in Fig. 1, adds the main parts 16, 17 of the picture which when the sheet is folded (Figs. 6 and 7) combines with 18 to show a plastic picture whose overlapping parts appear in several different planes.

70 The canopy 17 forming a separate portion of section B, when folded as shown in Fig. 7, extends in a horizontal

and a vertical plane. It may project through a slit (not shown) provided in a covering section.

All the printing appears on the "rear" side of the sheet.

In the embodiment of Fig. 9 all three sections B, C, D carry parts of the picture and are scored so as to partly cover and uncover each other, respectively.

Fig. 10 shows a card similar to Fig. 9, in which a fourth printed and scored section E participates in the formation of the picture.

Fig. 11 shows the application of the invention to articles made of transparent material (for instance cellophane or oil paper).

Fig. 12 shows how two narrow sections C and D can be employed as leaves of a triptych-door covering part or all of the picture.

Fig. 14 illustrates a modified form of a card according to this invention. Here the cover section does not comprise a frame whose edges serve as retainers of detached picture portions but a triangular section B smaller than the other sections and presenting two edges 19 by means of which cut-out portions of the pictures on sections C and D can be raised into other planes.

Fig. 13 shows how cards such as described in the foregoing can be fashioned to be placed on a table in vertical position. The covering frame-section B, through which appears a part of a lateral (picture) section, has a section 20 folded to afford an abutment 21 which supports the picture sections in vertical position.

The production of the plastic appearance is aided by the provision of double-folds such as indicated for instance in the dotted lines 22, 23 in Fig. 1, and 24, 25 and 26, 27 in Figs. 5 and 7.

The back and the covering sections may be held in the folded position by suitably fashioned fastening corner pieces 28 being inserted into slits 29 of another section (Fig. 1).

Obviously not only cards, but also other articles, for instance envelopes, books and other products mentioned in the first paragraphs of this specification, may be combined with plastic pictures according to this invention.

Obviously, the sheet with its coherent sections might

be composed of a number of separate sheets connected by gluing or in some other manner, without departing from the invention, however in that case the advantage of printing its components in a single operation might get lost.

I wish it to be understood that I do not desire to be limited to the details of the embodiments shown and described, for obvious modifications may occur to a person skilled in the art.

10 I claim:

1. As a new article, a sheet bearing on different sections of one of its surfaces all parts of a picture, a first section serving as a background and connecting a second and a third section, said third section being folded down 15 along a first line in superposition upon said first section and in this position displaying part of the picture, being scored to form a frame surrounding all parts of the picture, a second section being folded along a second line extending at right angles to said first line and being arranged between said first and said third sections, displaying in this position another part of the picture, which extends through said frame into a plane in front of said frame and is interleaved with parts of the picture on the second section so as to overlap them and said frame.

2. The article of claim 1, in which part of one of the second and third sections is folded twice along two closely adjacent lines in opposite directions.

3. The article of claim 1, in which the first and the third sections are bigger than the second section.
